ADJUSTABLE VENTILATOR

Maurice Prager, North Providence, R.I., assignor to Maurice Franklin Mfg. Company, a corporation of Rhode Island

Application November 13, 1956, Serial No. 621,930

1 Claim. (Cl. 98—118)

The present invention relates generally to ventilating devices, and more specifically to ventilators of the louver variety.

A primary object of the instant invention is the provision of a ventilating device for use in homes and other building structures wherein the amount of air passing therethrough may be easily and readily adjusted from the inside of the house or other building structure.

Another object of my invention is the provision of a ventilating device which enables a variable amount of air to pass therethrough but which at the same time is so constructed as to prevent the presence of a draft within the enclosure or structure with which said device is associated.

Another important object of my invention is the provision of a ventilating device of the general character described which preclude the passage therethrough of rain, snow, and the like, as well as insects, while at the same time freely enabling an adjustable amount of air to flow therethrough.

A further object is the provision of a ventilating device which may be easily, yet securely, mounted at any desirable location in the house or building in which it is being utilized.

An additional object of my invention is the provision of a ventilating device of the louver variety characterized by an ingenious simplicity of design, which enables the device to be simply and economically manufactured.

Still another object of the instant invention is the provision of a louver-type ventilator which enables an adjustable flow of air to pass through, and which is attractive in appearance, easy to operate, and highly efficient in use.

Other objects, features and advantages of the invention will become apparent as the description thereof proceeds when considered in connection with the accompanying illustrative drawings.

In the drawings which illustrate the best mode presently contemplated by me for carrying out my invention:

Fig. 1 is a front elevation of my ventilator, mounted in operative position on a wall support;

Fig. 2 is a rear elevation thereof;

Fig. 3 is a section, on an enlarged scale, taken on line 3—3 of Fig. 1; and

Fig. 4 is a fragmentary detail showing my novel and improved means for securely assembling the wire screen to the louver plate.

It has been found desirable to provide a ventilating device for homes or other building structures wherein an adjustable amount of air is allowed to pass therethrough, while at the same time the passage of snow, rain, insects, and the like, is prevented. Thus, there has been provided in accordance with the instant invention a ventilating device that is efficiently capable of accomplishing the above functions, but which, nevertheless, is ruggedly simple in design, whereby the number of separate elements necessary to make up my complete assembly is maintained at a minimum. As will be obvious, and as will become more

2

clearly apparent as the detailed description of my invention proceeds hereinafter, my ventilator construction provides an attractive, clean-cut appearance; and due to the ingenious simplicity of the arrangement of the parts, it is easy and economically feasible to manufacture. Furthermore, it is convenient to assemble and install, and once mounted in operative position, it will operate efficiently for extended periods of time, and probably for the life of the building structure with which it is associated, except, of course, for the possible replacement of the wire screen which forms a part thereof, should this particular element become clogged or otherwise damaged.

It will be understood that my ventilating device may be mounted at any desired location, such as at the sash or any other frame portion of a window, in a door, or in virtually any wall surface through which ventilation is desired by enabling the passage of a regulated quantity of air. Referring now to the drawings, there is shown a wall 10 through which it is desired to effect ventilation, and on which is mounted a ventilating device constructed in accordance with my invention. As will be seen most clearly in Fig. 3, the wall 10 has an outer surface 12, an inner surface 14, and an elongated opening 16 extending therethrough. It will be understood that the specific configuration of the opening 16 is determined by the shape of the ventilating device which covers same, but preferably, said opening is of elongated, oblong configuration. As will be obvious, and as afore-indicated, the opening 16 extends entirely through the wall 10, and hence provides a passageway for enabling air to flow therethrough.

On the outer surface 12 of the wall 10, there is mounted a louver plate, generally designated at 18. The plate 18 is preferably of extruded aluminum construction, although it will be understood that any other suitable material, metallic or otherwise, can be utilized if desired, and further, that the manufacturing techniques utilized to arrive at the finished plate, now to be described, are purely optional. As will be seen most clearly from Figs. 1 and 3, the plate 18 comprises a flat marginal flange portion 20 and a raised or dished central portion 22. It will be understood that the central portion 22 is substantially larger than the aforesaid opening 16 whereby the marginal flange 20 surrounds said opening and is adapted to engage and be secured to the surface 12 of wall 10.

The central portion 22 of louver plate 18 is provided with a plurality of outwardly extending louvers 24 which preferably are arranged in different and distinct series. Although I prefer to utilize three series of five louvers each, it will be appreciated that any desired number of series may be utilized, and further, that any desired number of louvers may be present in any one series. Preferably, the louvers 24 are disposed at an angle of 26° with the vertical, and it will be noted that each of said louvers has closed and beveled end portions 26 whereby the entry of undesirable weather conditions, such as rain, snow, or the like, is virtually prohibited. In fact, even air passing through the louvers 24 must infiltrate therethrough in an upward direction thereby insuring that no appreciable through draft will ever exist, it being obvious that such a draft would be both uncomfortable and unhealthy where my ventilator is associated with the living area of a house or other building.

In order to prevent the entry of bugs and other undesirable foreign particles through my ventilating device, there is provided a screen 28, preferably wire mesh, which screen is carried by the rear surface of louver plate 18. More specifically, the configuration of the screen 28 is such that it is adapted to be snugly received in abutting relation with the rear surface of the dished central portion 22 of the louver plate 18, and said screen is securely maintained in this position by means of integrally struck lugs 30, note Fig. 4. As will be obvious, the lugs 30 are

struck from the oppositely disposed ends of the marginal flange 20 and are bent back to tightly maintain the screen in abutting engagement with the rear surface of central portion 22. At the same time, the openings 32 which are formed as a result of striking the lugs 30 provide ready and convenient means for mounting the louver plate and screen assembly to the surface 12 of wall 10, such as by screws 34 or the like. Thus it will be seen that I have provided a highly simplified and yet effective construction for mounting the screen 28 in place and so maintaining it while the louver plate is being attached to its associated wall. Once the louver plate is securely mounted in position, the mounting of the screen 28 becomes even more secure since it is clamped between the surface 12 and the portion of plate 22 which surrounds the actual louvers, note Fig. 3.

On the inner surface 14 of the wall 10 there is provided a slidable plate assembly generally designated at 36. As will be noted, the assembly 36 comprises a support plate 38 very similar in configuration to the afore-described louver plate 18 in that it has a marginal flange portion 40 and a raised central portion 42 of a similar nature to the corresponding parts of said louver plate, note Fig. 2. The mounting or support plate 38 is secured to the surface 14 by any desirable means, such as screws 44, for example; and when so mounted, it is in oppositely disposed alignment with respect to louver plate 18, as will be seen most clearly from Fig. 3.

The central raised portion 42 of the plate 38 is provided with a plurality of rectangular cut-outs or apertures 46, each of which is in alignment with one of the series of the louvers 24 carried by louver plate 18. As will be noted, the height of the openings 46 is preferably slightly less than that of the opening 16, while the length of each of said cut-outs is somewhat less than the length of the individual louvers 24. Thus it will be seen that ventilated air will pass through the louvers 24, the screen 28, opening 16, and then through the cut-outs 46, whereby to flow into the area in which ventilation is desired.

In order that the flow of ventilated air may be simply and readily adjusted from within the enclosure being ventilated, I prefer to provide slidable means for either partially or completely blocking off the cut-outs 46. More specifically, the slidable blocking means takes the form of an elongated slide plate 48 having integrally extending rolled portions 50 extending from the upper and lower edges thereof. As will be clearly seen in Figs. 2 and 3, the rolled portions 50 extend through elongated slots 52 provided in the central raised portion 42 of the plate 38, the slots 52 and the portions 50 cooperating to enable a limited amount of sliding motion for the plate 48. Thus, in effect, the portions 50 function as combined guide means and handle means, since as will be obvious, they not only define the sliding movement of the plate 48, but at the same time, they also provide readily accessible means for imparting said movement thereto. The plate 48 is further characterized by the provision of a plurality of rectangular apertures 54, each of which is of substantially the same size as the aforedescribed apertures 46 in the plate 38. As will be seen most clearly from Fig. 3, the slidable plate 48 fits snugly between raised portion 42 and the surface 14, it being understood, however, that the plate 48 is gripped just sufficiently to prevent it from inadvertently sliding to open or closed position, but not so

tightly as to make it difficult to impart sliding movement thereto when desired. When the rolled handle portions 50 are at one extremity of their travel in the slot 52, it will be understood that the cut-outs 54 and 46 are in perfect alignment, in which condition a maximum flow of ventilated air passes through my device. Looking at Fig. 2, this condition would occur when the handle 50 is at its extreme right-hand position. As the handle 50 is moved toward the left, however, the slidable plate 48 will commence to block off the cut-outs 46 whereby to reduce the flow of air passing through my device until the handle 50 has reached its extreme left-hand position wherein the apertures 46 will be completely blocked off, and hence, no air at all can pass through the device.

Thus it will be seen that there has been provided in accordance with the instant invention a ventilating device characterized by extreme simplicity, but which, nevertheless, is simple and effective in operation. As will be obvious, my construction comprises a minimum of separate elements, thereby facilitating the manufacture and assembly thereof, and at the same time keeping the cost at a feasible level. As afore-indicated, any number of series of louvers may be utilized, it being understood that the number of series will preferably determine the number of cut-outs in the plates 38 and 48.

While there is shown and described herein certain specific structure embodying the invention, it will be manifest to those skilled in the art that various modifications and rearrangements of the parts may be made without departing from the spirit and scope of the underlying inventive concept and that the same is not limited to the particular forms herein shown and described except in so far as indicated by the scope of the appended claim.

I claim:

35 A ventilator for attachment to an apertured wall, said ventilator comprising a first plate having a flat marginal flange portion and a raised central portion, a plurality of louvers extending from said central portion, a screen member having substantially the same configuration as said central portion whereby it is adapted to be snugly received in abutting engagement with the underside of said central portion, and means for maintaining said screen in said abutting engagement, said means comprising a plurality of lugs integrally struck from said marginal flange portion and bent back over said screen, said struck portions providing mounting apertures for said first plate, said mounting apertures being inwardly spaced from the outer peripheral edge of said first plate.
